UNITED STATES PATENT OFFICE.

JULIUS SCHÜLLINGER, OF NEW YORK, N. Y., ASSIGNOR TO HUYLER'S, OF NEW YORK.

DESIGN FOR A BOX.

SPECIFICATION forming part of Design No. 34,665, dated June 18, 1901.

Application filed May 20, 1901. Serial No. 61,195. Term of patent 14 years.

To all whom it may concern:

Be it known that I, JULIUS SCHÜLLINGER, a citizen of the United States, residing at the city of New York, in the borough of Manhattan and State of New York, have invented a certain new and original Design for Boxes, of which the following is a full, clear, and exact description.

The figure in the drawing is a perspective view of a rectangular box, showing my new design applied to one side or panel thereof.

The leading or material feature of my design consists of a large oval or egg-shaped figure A, covering a large portion of a side or panel of the box. This oval apparently covers the middle portion of a horizontal band B, which extends entirely across the panel, its end portions only being seen. Above and below each end of the band are plain surfaces

C, inclosed by an arabesque line c on one side, the edge of the band B on another side, and the edge of the oval figure on another side. This inclosed space and the ends of the band are of contrasting colors. Springing from an angle in each of the arabesque lines are tendril-like scrolls e.

Having described my invention, what I claim as new, and desire to secure by Letters Patent, is—

The design for a box as herein shown and described.

In witness whereof I subscribe my signature in presence of two witnesses.

JULIUS SCHÜLLINGER.

Witnesses:

FRANK DEK. HUYLER,
LOUIS M. FULTON.
